C. P. Arnold

United States Patent Office.

C. P. ARNOLD, OF NEW YORK, N. Y., ASSIGNOR TO THE GYROSCOPIC-TOP COMPANY, OF SAME PLACE.

Design No. 3,114, dated July 21, 1868.

DESIGN FOR THE FRAME OF A GYROSCOPIC TOP.

The Schedule referred to in these Letters Patent and making part of the same.

TO ALL WHOM IT MAY CONCERN:

Be it known that I, C. P. ARNOLD, of the city, county, and State of New York, have invented an improved Design for the Frames of Gyroscopic Tops; and I do hereby declare that the following is a full, clear, and exact description of the same, reference being had to the accompanying drawing, making a portion of this specification, in which—

Figure 1 is a side view of a gyroscopic top, having its frame made according to my design.

Figure 2 is a plane view of the same.

Similar letters of reference indicate corresponding parts in both figures.

The frame is represented at A in the drawings, and has its two opposite sides formed on salient curves or arcs, *a*, from which, to the ends *b*, the intermediate portions are shaped on re-entrant curves, all as shown in fig. 1, the curvature of the portions *a b* being somewhat less than that of the other or side portions *a*. One of the ends, *b*, of the frame is formed straight across, as shown at *a'*, and the opposite end extends outward from the curved portions, just hereinbefore described, in the shape of a square, as shown at *a**. The curved portions *a* and *a b* are made of circular shape in their transverse section.

What I claim as my invention, and desire to secure by Letters Patent, is—

The design and configuration, herein described and shown, of the frame of a gyroscopic top.

C. P. ARNOLD.
